SKIRT AND BREECHES HANGER

George M. Nelson, Renton, Wash.

Application November 28, 1939, Serial No. 306,548

2 Claims. (Cl. 223—96)

This invention aims to provide a simple device for suspending a garment, such as a skirt or a pair of breeches, novel means being provided for admitting the cuffs of a pair of breeches, or the top hem of a skirt, and novel means being supplied for manipulating the device.

Fig. 1 shows, in perspective, a device constructed in accordance with the invention; and

Fig. 2 is a top plan.

10 The skirt and breeches hanger forming the subject matter of this application preferably is made out of wire or similar material, in a single piece, and having some resiliency. It includes a U-shaped clamp 1, comprising cooperating jaws 15 2, merging at one end into the lower members 3 of a broadened, upstanding stiffening eye 4, including upper members 5, which are prolonged to form the spaced side pieces 6 of a broadened, stiffening hand grip 7, the grip overhanging the clamp, the side pieces 6 being joined together 20 by twisting or otherwise, as at 8, adjacent to the eye 4, the inner ends of the side pieces 6 being joined together, by twisting or otherwise, as shown at 9, and one of the side pieces 6 being 25 provided with a suspension element 10, such as an upwardly projecting hook.

The operator lays hold of the grip 7. The skirt or a pair of breeches is introduced between the jaws 2, the cuffs of the breeches, or the hem 30 of the skirt, passing through the enlarged eye 4.

The article is further characterized by the fact that the jaws 2 diverge, where they merge into the lower members 3 of the eye 4, to define an entering throat 11.

5 The device is simple in construction, but will be found thoroughly advantageous for the ends in view, capable of being manufactured at small cost and effective to keep the creases in a garment and to avoid wrinkles.

A mechanic who abides by what is claimed, 10 may make changes in the precise structure shown, without departing in corresponding measure from the spirit of the invention.

What is claimed is:

1. A skirt and breeches hanger made from a 15 single piece of stock, and including a U-shaped clamp comprising cooperating jaws merging at one end into the lower members of a broadened, upstanding eye, including upper members, which are prolonged to form the spaced side pieces of 20 a hand grip overhanging the clamp, the side pieces being joined together adjacent to the eye, the inner ends of the side pieces being joined together, and one of the side pieces being supplied with a suspension element.

2. The skirt and breeches hanger of claim 1, 25 further characterized by the fact that the jaws diverge, where they merge into the lower members of the eye, to define an entering throat.
